[57] **ABSTRACT**

The invention disclosed provides a new improved water dispersable chlorinated solvent and method for cleaning surfaces by high pressure.

5 Claims, No Drawings

WATER DISPERSABLE CHLORINATED SOLVENT AND METHOD

The present invention relates to a new method and composition for cleaning the interior of a container vessel by means of high pressure sprays.

In summary, this invention provides for cleaning surfaces with cleaning compositions comprising applying an aqueous solution containing the cleaning composition to the surface to be cleaned, and rinsing the composition from the surface with water.

Spray cleaning of surfaces such as interiors of tank trucks, railway tank cars, storage tanks, mixing kettles, ship's holds, and other similar areas has been used where the drying or curing of paints or resinous soils make it impossible to clean by the usual chemical cleaning operations. In general, strong, hot caustic solutions have been used to remove these soils and are generally ineffective.

The present composition has been found to be highly effective by providing a water dispersable solvent which can be used through standard high pressure, high temperature equipment for removing resins or other soils which conventional cleaning solutions will not remove. This composition can also be applied as an additive to standard caustic solutions.

Cleaning is done using a blend of chlorinated solvents dispersed in hot water rather than spraying them undiluted and cold. The present composition accomplishes suspension of the blend of solvents rather than emulsification.

The present composition, generally stated, comprises a blend containing from 0 to about 75% methylene chloride, from about 25 to about 99.9% of low volatility chlorinated solvent such as orthodichlorobenzene, propylenedichloride or trichloro-ethylene, and from about 0.1 to about 25% of emulsifier which is added from about 1 to about 25% concentration to hot water or to a standard caustic solution at 120° to 190° F. A standard cleaning operation at this temperature will remove almost any soil from a container's interior. The emulsifier or combination of emulsifiers in the formulation should be in sufficient concentration only to briefly suspend droplets of solvent in the water. The turbulence caused by the cleaning operation will keep the solvent suspended and the solvency of the solvents will not be lost by tying them too tightly into the water solution.

When used herein, all parts are given by weight unless indicated otherwise.

The present composition also contains an emulsifier such as an alkyl benzene sulfonate having from 8-18 carbons in the alkyl group. Suitable alkylbenzene sulfonates include the tetrapropylene benzene sulfonate and linear alkylbenzene sulfonates having about 12 carbons in the alkyl group, the latter being preferred because they are biodegradable and do not create disposal problems.

The composition may also contain an emulsifier such as phosphate esters, alkali metal and preferably sodium salts, sold under the trade name Emcol PS-222 by Witco Chemical Co. of New York City, and alkoxy-alkyl phosphate esters having from 6-18 carbons,

preferably from 10 to 14 carbons, in the alkyl group and from 2-6, and preferably 4 moles of alkoxylate. The preferred alkoxylate is ethylene oxide.

In addition, a combination of emulsifiers can be used such as an alkyl sulfonate having from 16 to 20 carbons in the alkyl group combined with an alkyl benzene sulfonate having from 12 to 16 carbons in the alkyl group. Suitable alkyl sulfonates include sulfonated castor oil having about 18 carbons in the alkyl group. Suitable alkyl benzene sulfonates include the benzene sulfonate of myristic acid having about 14 carbons in the alkyl group.

The cleaning composition may contain the alkali metal (sodium, potassium and amine) salts of fatty acid sulfonates having from 8-18 carbons in the fatty acid group, and lower alkyl benzene sulfonate having from 1-3 carbons in a lower alkyl group. The preferred fatty acid sulfonate is the amine salt of lauroleic acid sulfonate or dodecanoil acid sulfonate. The preferred lower alkylbenzene sulfonates include xylene, toluene, ethylbenzene, and isopropylbenzene sulfonates. Sulfonates made from xylene include orthoxylene sulfonate, metaxylene sulfonate, paraxylene sulfonate, and ethylbenzene sulfonate. Commercial xylene sulfonates usually contain metaxylene sulfonate as the main ingredient.

Additional useful emulsifiers include materials such as phosphate esters, sodium salt of a coconut derived dicarboxylate, sulfonated castor oil, sulfated castor oil, ethoxylated monolaurate, lauric alkylolamines and the like mixtures of these various materials may also be used.

The critical factor of the emulsifier used herein is that it be sufficiently low in concentration and yet effective to suspend the major portion of the solvents for a period of time from about 0.5 to about 5 minutes.

The preferred compositions according to this invention are shown in Table A.

TABLE A

INGREDIENT	PARTS BY WEIGHT
Methylene Chloride	0-40.0%
Low Volatile Chlorinated Solvent (propylenedichloride)	60.0-99.5%
Emulsifier (alkyl benzene sulfonate)	0.5-10.0%

After the cleaning solvent is applied to the soiled surface and when the cleaning action is complete, the residual cleaning composition can be rinsed from the surface, preferably with a high pressure water wash. The rinse can contain neutralizing chemicals, defoaming compounds, and conventional rinse surfactants to promote the rinsing action and prevent deposit of residue on the cleaned surfaces.

The invention will be further illustrated by the following specific but non-limiting examples.

EXAMPLE 1

1 x 2 inch steel panels were coated with two moderately difficult to remove resins and one very difficult to remove resin and allowed to air cure for a 16 hour period at room temperature. The panels were then immersed in the dispersions below for ½ hour at the temperatures noted and then rinsed. The dispersions were periodically stirred:

TABLE B

INGREDIENT	PARTS BY WEIGHT	PARTS BY WEIGHT
Water	95.00	92.5
Caustic Cleaner	—	7.5
Alkyl sulfonate	0.15	—
Sulfonated Castor Oil	0.15	—
Methylene Chloride	1.55	—
Propylene Dichloride	3.15	—
Temperatures	100.00 120°F to 140°F.	100.00 160°F to 180°F.
RESULTS		
Resin No. 1 (Rohm & Haas Acryloid A-101)	Removed	Slightly Softened
Resin No. 2 (Rohm & Haas HA-8 Latex)	Removed	Removed
Resin No. 3 (Rohm & Haas P-681 Resin)	Removed	Removed

Similar results were obtained when the alkyl sulfonate and sulfonated castor oil were replaced with the following:

1. 0.3% dimethyl dicoco ammonium chloride
2. 1.0% sulfonated castor oil
3. 0.3% phosphate ester

20 The following formulation was dispersed in a 7.5% solution of a caustic cleaner and in water and the same cleaning test as in Example 2 above was run.

EXAMPLE 3

INGREDIENTS	PARTS BY WEIGHT	PARTS BY WEIGHT
Methylene Chloride	33.0	33.0
Propylene Dichloride	66.5	66.5
An Alkyl benzene sulfonate	0.5	0.5
Dilution medium	7.5% caustic cleaner solution	Water
RESULTS		
Resin No. 1 (Rohm & Haas Acryloid A-101)	Almost 100% removed	Almost 100% Removed
Resin No. 4 (Glidden Oleoresinous Can Coating)	Removed	Removed
Resin No. 5 (Glidden Vinyl Can Coating)	Greatly Softened	Greatly Softened

4. 0.2% dodecyl benzene sulfonate
5. 0.6% phosphate ester + 0.4% nonyl phenol

EXAMPLE 2

The following were dispersed in water at the given concentrations and the same cleaning test as in Example 1 above was run at 120° to 140°F.. The two moderately difficult to remove resins were replaced with two difficult to remove resins.

40 When the cleaning compounds are applied to the surface being cleaned, splash-back, misting, and irritating vapors and mists are greatly reduced.

45 Obviously, many modifications and variations of the invention as hereinabove set forth can be made without departing from the essence and scope thereof, and only such limitations should be applied as are indicated in the claims.

What is claimed is:

1. A method for cleaning surfaces which comprises applying a blend of from 0% to about 75% by weight methylene chloride, from about 25% to about 99.9% by weight of a low volatility chlorinated solvent, and from

TABLE C

INGREDIENTS	PARTS BY WEIGHT	PARTS BY WEIGHT	PARTS BY WEIGHT	PARTS BY WEIGHT
Methylene chloride	33.0	32.0	23.0	19.0
Propylene dichloride	67.0	65.0	47.0	38.0
Phosphate ester	—	3.0	18.0	25.0
Ethoxylated nonyl phenol	—	—	12.0	18.0
% Emulsified in 7.5% cleaner solution	100.0	100.0	100.0	100.0
RESULTS	5.0%	5.0%	6.9%	8.5%
Amount of settling during cleaning operation	Extensive Greatly Softened	Extensive Almost 100% Removed	Some Some Soften- ing	None No Effect
Resin No. 1 (Rohm & Haas Acryloid A-101)	Removed	Removed	Removed	Greatly Softened
Resin No. 4 (Glidden Oleoresinous Can Coating)	Softened	Removed	Softened	Slightly Softened
Resin No. 5 (Glidden Vinyl Can Coating)				

about 0.1 to about 25% by weight of an emulsifier, said blend being disposed in water in an amount from about 1 to about 25% by weight and applied to the surface at a temperature of 120°F. to 190°F., and thereafter rinsing the applied solution from the surface with water.

2. The method of claim 1 wherein the chlorinated solvent is a member of the group consisting of orthodichlorobenzene, propylenedichloride and trichloroethylene.

3. The method of claim 1 wherein the emulsifier maintains an emulsion for a period of time from about 0.5 to about 5 minutes.

4. A cleaning composition which comprises in combination from 0% to about 75% by weight methylene chloride, from about 25% to about 99.9% by weight of a low volatility chlorinated solvent selected from the group consisting of orthodichlorobenzene propylenedichloride and trichloro-ethylene, and from about 0.1 to about 25% by weight of an emulsifier capable of maintaining an emulsion for a period of time for about 0.5 to about 5 minutes in water at a cleaning composition concentration of 1 to about 25% by weight.

5. The composition of claim 4 wherein the emulsifier is alkyl benzene sulfonate having from 8-18 carbon atoms in the alkyl group.
